HASSOCK

Fred W. Niemann, Chicago, Ill.

Application June 5, 1953, Serial No. 25,344

Term of patent 14 years

(Cl. D15—8)

To all whom it may concern:

Be it known that I, Fred W. Niemann, a citizen of the United States, residing at Chicago, in the county of Cook and State of Illinois, have invented a new, original, and ornamental Design for Hassock, which the following is a specification, reference being had to the accompanying drawing, forming a part hereof.

Fig. 1 is a perspective view of a hassock showing my new design;

Fig. 2 is a perspective view of the opposite side of the hassock;

Fig. 3 is a side view, with the cover upside down;

Fig. 4 is a view showing the interior of the hassock and a bottom plan view of the cover.

I claim:

The ornamental design for a hassock, as shown.
